UNITED STATES PATENT OFFICE.

ERVIN T. TREFETHEN, OF BOSTON, MASSACHUSETTS, ASSIGNOR OF ONE-HALF TO ARTHUR O. NORTON, OF COATICOOK, CANADA.

DOUBLE-ACTION JACK.

SPECIFICATION forming part of Letters Patent No. 613,949, dated November 8, 1898.

Application filed July 18, 1898. Serial No. 686,226. (No model.)

To all whom it may concern:

Be it known that I, ERVIN T. TREFETHEN, of Boston, in the county of Suffolk and State of Massachusetts, have invented a new and Improved Double-Action Jack, of which the following is a specification, reference being had to the accompanying drawings, in which—

Figure 1 is a side elevation of my new automatic lowering or double-action jack with the lifting-bar in its lowest position and the pawl-controller out of the path of the lifting-pawls. In this view parts of the jack-standard are broken away for greater clearness and the jack is shown with the parts in position to lift. Fig. 2 is a central vertical section of the jack with the parts in the same position as in Fig. 1. Fig. 3 is a transverse sectional view at line 3 3 of Fig. 1. Figs. 4 and 5 are views of opposite sides of the handle provided with reverse cams, and Figs. 6 and 7 are perspective views of the two pawls. Fig. 8 is a side elevation, partly in section, showing the lifting-bar raised and the pawl-controller in the path of the pawls, the parts being now in position for automatically lowering the lifting-bar. Fig. 9 is a front view of my new jack, partly in section, on line 9 9 of Fig. 8.

In the accompanying drawings, illustrating the principle of my invention and the best mode now known to me of applying that principle, A is the jack-standard, and B the lifting-bar. Standard A is formed with a lengthwise-extending recess a to receive lifting-bar B, the recess being bridged across at a' to inclose the lifting-bar and form an inclosing guideway therefor. The lifting-bar is provided with the usual head b and angularly-projecting foot b', which bottoms, preferably, in the angularly-extending portion a² of the recess a. The lifting-bar is provided on its inner face with teeth b². The inner wall a³ of standard A extends only part way from the bottom of the standard toward the top thereof, so as to have an opening at a⁴ between the side walls a⁵ of the standard for engagement of the pawls D and D' with teeth b². In the rearwardly-extending wings a⁶ and a⁷ of standard A the pawls D and D' are loosely mounted on cams d and d', fast on opposite sides of the inner end portion d² of

the handle D². Cams d and d' are reversely mounted, cam d extending forwardly and cam d' extending rearwardly of the journal D³, which passes through the wings and the intermediate portions of the cams and handle. Pawl D is provided toward its free end with a lateral projection d⁸, which extends under the free end portion of pawl D', and pawl D is also provided about opposite the journal D⁸ with a rearwardly-projecting lug d⁴, which rests on the pin f, mounted and forming part of the direction - controlling frame F. Near the forward end of the pawl d a lug d⁵ is provided, this lug being adapted to engage the stop-rib a⁸, which projects from the inner face of wing a⁷. Pawl D' is formed at its rear portion with a rearwardly-projecting lug d⁶, which rests on the pin f', mounted in frame F. This frame is provided with end journals f² f², which are mounted in the wings of the standard, and it is also provided with laterally-projecting endwise-chambered projections f³ and f³, in which the pins f and f' are respectively mounted. These pins are each provided with a shoulder f⁴ toward their upper ends, and between the shoulder f⁴ of each pin and the bottom of the chamber in which the pin is mounted there is a coiled spring f⁵. The bottom of each chamber is centrally perforated, and the butt-end of each pin passes freely through the perforation and is secured in place by any suitable confining device, such as a cross-pin f⁶. One journal f² is extended beyond the outer side wall of one of the wings of the standard and supports a lock-block f⁷, which is journaled at f⁸ on the extension f⁹ of the journal f², so as to be moved from and toward the outer face of the opposed wing of the standard, where there are a pair of abutments f¹⁰, between which the free end of the lock-block f⁷ is confined when it is desired to keep the pins f and f' upright—that is, in operative position in respect to the cam-lugs d⁴ and d⁶. The lock-block is conveniently held in this position by the stress of a spring f¹¹, mounted in its recess f¹² and bearing against an opposed surface of the extension f⁹. To prevent undue wear of the cams, their work-surfaces are preferably made by shrinking rings of appropriate quality of steel on the cam-bodies which

are preferably integral with the casting that forms the handle; but the reverse construction, shown as a modification, below described may be employed if desired. It is desirable to keep the journal from turning and consequently I provide means therefor, the preferred means consisting of a flat bearing-surface on the journal-head and an opposed contacting flat-faced lug on one of the wings of the standard. The foregoing parts constitute merely the preferred construction of jacks embodying my invention, and they may be altered in various ways without departure from my invention.

15 The operation of my new jack is as follows: The lifting-bar being down and the position-controlling frame being turned to carry pins out of contact with the cam-lugs, the free ends of both pawls gravitate toward the toothed side of the lifting-bar, all of which will be clear from Fig. 1. An upward movement of handle D^2 carries pawl D' upwardly into contact with one of the teeth, and the same movement of the handle retracts pawl D , so that this pawl just rests on the apex of a tooth and is ready to drop under the face of that tooth when the handle shall be lifted a little higher. Continued upward movement of the handle compels pawl D' to lift the bar B , and as this pawl D' is pushed sufficiently to permit pawl D to pass the apex and engage the under face of the tooth on which it rests. A complete downward movement of the handle now causes pawl D to lift the bar B , and as this pawl D is pushed upward by its own cam d the cam d' of pawl D' retracts pawl D' and causes it to pass over the apex of and drop under the face of the next lower tooth. The pawls D and D' lift alternately and are alternately brought into position for lifting, one of the pawls being pushed upwardly at each upstroke of the handle, one being pushed upwardly at each downstroke of the handle, and one being always under a tooth. To lower the lifting-bar, the position-controlling frame F is swung into position to bring its pins f and f' under the cam-lugs d^4 and d^6 . Supposing handle D^2 to be in its highest position, as shown in Fig. 8, pin f is brought against lug a^4 and pawl D , the spring of pin f being compressed (see Fig. 9) and its tension then lifting the free end of pawl D clear of the teeth on bar B . Pawl D' is now in engagement with a tooth on the lifting-bar B . Downward movement of the handle retracts pawl D' from the tooth and moves the free end of pawl D into engagement with a tooth, the forward movement of the pawl D carrying its lug d^4 out of engagement with the pin f and the rearward movement of pawl D' carrying its lug d^6 against pin f' , thereby compressing the spring of that pin and causing the spring when the free end of pawl D' is out of the way of the teeth to move the free end of pawl D' back out of position to engage the teeth. The lifting-bar is thereby lowered.

The cams on the handle are shown faced with hardened-steel rings; but that feature of my invention is not claimed herein, as it is claimed in another application of even date. 70

What I claim is—

1. In a jack, the combination of a standard having a guideway for the lifting-bar; a toothed lifting-bar in said guideway; a handle fulcrumed on the standard, and provided on opposite sides with reverse cams; a pawl mounted on each cam and alternately movable into and out of engagement with teeth on the lifting-bar; a movable frame comprising a plurality of spring-controlled pins one 80 for each pawl; and means for locking said frame in position to keep said pins in the paths of the pawls. 75

2. In a jack, the combination of a standard having a guideway for the lifting-bar; a toothed lifting-bar in said guideway; a handle fulcrumed on the standard and provided on opposite sides with reverse cams; a pawl mounted on each cam and alternately movable into and out of engagement with teeth on the lifting-bar; a movable frame having a transverse portion journaled in the standard between the foot of the standard and the butt-ends of the pawls, said frame having endwise-chambered projections which extend laterally of the transverse portion of the frame; a yielding pin mounted in the chamber of each projection; and means for locking said frame in a position which brings said yielding pins into the paths of the butt-ends 100 of the pawls, the pawls and pins alternately coöperating during the recession of the lifting-bar, to move the pawls alternately under a tooth of the lifting-bar while the other pawl is moving to engage another tooth of the lifting-bar. 95

3. In a jack, the combination of a standard having a guideway for the lifting-bar; a toothed lifting-bar in said guideway; a handle fulcrumed on the standard; a pair of 110 pawls pivotally mounted on the lever at different sides of the fulcrum of the lever; a movable frame journaled in the standard and extending opposite the butt-ends of the pawls; means for locking said frame in its operative 115 position during the lowering operation; and yielding devices which are between the frame and the butt-ends of the pawls during the lowering operation, and which then alternately connect the frame with the butt-ends 120 of the pawls, to release one pawl from a tooth on the rack while the other pawl is moving under another tooth on the rack. 125

In testimony whereof I have signed my name to this specification, in the presence of two subscribing witnesses, on this 8th day of July, A. D. 1898.

ERVIN T. TREFETIEN.
